CLAIM

Related U.S. Application Data

(62) Division of application No. 29/463,735, filed on Feb. 20, 2014, now Pat. No. Des. 790,557.

The ornamental design for liquid crystal display (LCD) for operating the state of home appliances with graphical user interface, as shown and described.

DESCRIPTION

(30) **Foreign Application Priority Data**

Aug. 21, 2013 (JP) 2013-019041
Aug. 21, 2013 (JP) 2013-019044

FIG. 1 is a front, top and right side perspective view of a liquid crystal display (LCD) for operating the state of home appliances with graphical user interface, showing our new design;

(51) **LOC (11) Cl.** **14-04**

FIG. 2 is a front view thereof;

(52) **U.S. Cl.**

FIG. 3 is a rear view thereof;

USPC **D14/486**

FIG. 4 is a left side view thereof;

(58) **Field of Classification Search**

FIG. 5 is a right side view thereof; and,

USPC D14/485-495
CPC G06F 3/04817; G06F 3/0362; G06F 3/048;
G06F 3/04842; G06F 3/04847; G08B
13/19619; G08B 13/19636; G08B 17/10;
G08B 17/113; G08B 21/10; G08B 25/10;
G08B 25/007; G08B 25/009; G08B
29/14; G08B 29/188; G08B 29/24; H04N
5/2254; H04N 5/2256; H04N 5/23206;
H04N 5/33; H04N 7/18; H04N 21/2743;

FIG. 6 is a top plan view thereof.

The broken line showing in FIGS. 1-6 of a tablet type computer illustrates the environment of the article of manufacture. The broken line showing in FIGS. 1 and 2 of a display panel or screen, and text, illustrates portions of the article of manufacture. None of the broken lines form part of the claimed design.

1 Claim, 3 Drawing Sheets
